UNITED STATES PATENT OFFICE.

SIMEON S. JACKSON, OF BOSTON, MASSACHUSETTS, ASSIGNOR TO THE STAFFORD COMPANY, OF READVILLE, BOSTON, MASSACHUSETTS, A CORPORATION OF NEW JERSEY.

WEFT-REPLENISHING LOOM.

1,276,534.

Specification of Letters Patent. Patented Aug. 20, 1918.

Application filed August 22, 1914. Serial No. 858,014.

To all whom it may concern:

Be it known that I, SIMEON S. JACKSON, a citizen of the United States, residing at Readville, Boston, in the county of Suffolk, 5 State of Massachusetts, have invented a certain new and useful Improvement in Weft-Replenishing Looms, of which the following is a specification, reference being had therein to the accompanying drawings.

10 The features of the invention are applicable to shuttle-changing weft-replenishing looms on the order of that shown and described in U. S. Letters Patent No. 945,722, dated January 4, 1910. However, they are 15 not necessarily restricted to employment in the particular type of loom illustrated in the said patent, and I contemplate employing embodiments of the principles of the invention in bobbin-changing looms.

20 One feature of the invention consists in means for saving the starting ends of the weft or filling of the stack of reserve weft-carriers occupying the hopper or magazine of a weft-replenishing loom from injury due 25 to cutting or chafing between the portion of the said weft-carriers which contact with one another. A second feature of the invention consists in improved means for insuring that the portion of weft or filling extending 30 from the selvage of the web being woven to an ejected filling-carrier, otherwise known as the trailing weft-end, shall be acted upon by the weft-parting device that is employed to sever the same between the said weft- 35 carrier and the said selvage. Other features are presented hereinafter.

The drawings show embodiments of the said improvements in the best forms which I have thus far contrived, but the construction and arrangement of the parts may vary 40 more or less in practice to meet requirements and conditions of use.

In the drawings,—

Figure 1 shows in end elevation a portion 45 of the magazine-end of a weft-replenishing loom of the same general character as that shown and described in the patent mentioned above, with certain of the said embodiments of the improvements applied thereto. The 50 parts are shown in positions assumed by them during the regular running of the loom.

Fig. 2 shows in plan certain of the parts of Fig. 1.

Fig. 3 is a rear elevation of the hopper or 55 magazine and parts immediately adjacent the same.

Fig. 4 is a view similar to Fig. 1, but showing certain of the parts in positions assumed by them during the performance of 60 the change operations.

Fig. 5 is a view, partly sectional and looking from the middle of the width of the loom toward the magazine-end of the latter, showing a second form of embodiment of 65 the improvements in devices for taking care of the trailing weft-end, the trailing-weft catcher being in the position maintained by it during the regular running of the loom.

Fig. 6 is a view similar in character to 70 Fig. 5 but showing certain parts in the positions assumed by them during the performance of the change operations.

Figs. 7 and 8 are sectional views on the order of Figs. 5 and 6 showing a slightly different construction of the trailing-weft 75 catcher devices.

Having reference to the drawings,—

Only such parts are shown, in addition to those directly involved in the invention, as 80 are necessary to an understanding of the relations and nature of the invention itself.

Portions of one side-frame 1 of the loom and of the breast-beam 2, the lay-beam 3 and one lay-sword 4 are shown. The movable front-plate of the shuttle-box at the replenishing or magazine-end of the loom is shown at 5, 6 being the rocker with which the said front-plate is connected, and 7 the motion-transmitting rod through which the 85 said rocker and front-plate are operated to raise and lower the front-plate to open and close said shuttle-box. Only a portion of the said rod is represented. At 8 is indicated the change-shaft which in the patent 90 aforesaid operatively controls the instrumentalities by which the weft-replenishing operations are performed.

At 9 is represented the hopper or magazine for reserve shuttles *x*, *x*, etc., the said 100 hopper or magazine being mounted, as usual, at one end of the breast-beam. It has as usual opposite ends which are V-shaped in cross-section, and thus conform 105 interiorly to the shape of the shuttle-ends which occupy them. As is well understood, the reserve shuttles that are stacked up in the hopper or magazine rest one on top of

another therein, and when the bottom shuttle is transferred from the lower part of the hopper or magazine to the lay in effecting weft-replenishment the shuttles that remain in the hopper drop within the latter. In thus dropping they are guided vertically by the end-walls of the hopper or magazine. At 10 is a holder with which, as usual, the starting ends of the weft or filling threads carried by the reserve shuttles occupying the hopper or magazine are engaged, the purpose of such engagement being that when one of such shuttles is transferred from the hopper or magazine to the lay, and then picked through a shed in the warp-threads, the weft or filling contained in such shuttle and made fast to the holder 10 will be drawn out through the delivery-eye of the shuttle, as required for the purposes of weaving. Various forms and arrangements of starting end-holders are known in the art. I have shown a common form and arrangement comprising a peg or the like mounted upon and projecting from the upper portion 25 of the inner rear wall of the hopper or magazine. The extremities of the starting ends of weft or filling are made fast to the said peg by being wrapped around the same.

For a clearer understanding of the objects, etc., of the first portion of the invention, reference may be made to the fact that when in place upon the lay of a loom a shuttle presents its delivery-eye toward the front. For this reason, the reserve shuttles α , α' , etc., are placed in the hopper or magazine 9 with their delivery-eyes turned to the front. From this it follows that since the holder 10 for the starting ends α , α' , etc., of the weft or filling threads carried by the said shuttles is mounted, as above described, upon the inner rear wall of the hopper or magazine, the said starting ends extend from the said delivery-eyes rearward through between the reserve shuttles on their way to the starting weft-end holder. In practice heretofore the starting ends have passed directly between the contacting body-portions of the respective shuttles in the hopper or magazine, and have been subjected to the pressure of shuttles resting upon them. From this, and the constant motion of the shuttles in the hopper or magazine, due to the jarring of the loom when in operation, the said ends have been chafed 50 and thereby cut or weakened so as to break occasionally under strain.

In accordance with the first portion of my invention, I provide a guide by which the starting-ends α , α' , etc., of weft, extending from the delivery-eyes of the reserve shuttles α , α' , etc., in the hopper or magazine and through between such shuttles from front to rear on their way to the weft-end holder 10, are kept out from between the portions of the shuttles which

make contact with one another. A guide embodying this portion of my invention and subserving the described function is shown at a . See, more particularly, Fig. 3. This guide is constructed and located to hold the starting-ends in the open spaces between the tapering ends or tips of the shuttles, where the starting ends are entirely free from pressure. It is so constructed and supported as to permit a weft-end drawn part way out through the delivery-eye of a shuttle either just placed in the hopper or magazine or about to be placed therein, to be passed around the guide and be engaged therewith, and then have its free extremity engaged with and wrapped around the weft-holding peg; and also to permit the weft-end to be engaged with the guide with equal readiness in case its extremity has been engaged with the weft-holder before the shuttle has been placed in the hopper or magazine. It also is so constructed and supported as to provide for the unobstructed escape therefrom of the starting weft-end connected with a shuttle transferred to the lay. I have herein shown the guide as located at the rear side of the hopper, which is the preferable location, although I do not limit myself in all cases to this location. It also is shown as formed of wire, although this is not indispensable. Its portion for holding the starting weft-ends out from between the contacting portions of the shuttles occupies a vertical position adjacent the outer end of the hopper or magazine, parallel with the vertical edge of the rear wall of the corresponding end-portion of the hopper or magazine. The said wall is reduced in width so that it merely laps by the extreme tips of the shuttles sufficiently to confine the outer ends of the shuttles within the outer portion of the hopper or magazine. As a convenient manner of supporting the guide a , the latter at its top and bottom is connected by horizontal extensions b , c , of the wire to the rear wall of the inner end of the hopper or magazine, to which wall the extremities of the said extensions are made fast at c , f . The upper end of the guide a is provided with an upwardly and outwardly curved beak or horn d , Fig. 3, the shape of which facilitates the operation of engaging a starting weft-end with the guide, by enabling the said starting weft-end, held in one hand of the weaver, to be swung around said beak or horn and the upper portion of the guide by an easy movement of the hand in carrying the said end to and then wrapping it around the weft-holding peg 10. The said beak or horn is produced by doubling the wire upon itself and giving it an outward bend.

Fig. 3 of the drawings shows more clearly the relations of the upright guide a and the manner in which starting weft-ends drawn

out from the delivery-eyes of the shuttles loop around the said guide and extend thence to the weft-end holding-peg 10, and from Fig. 3 it will be apparent how the 5 portions of the starting weft-ends which loop around the said upright guide *a* will slide down the said guide as the shuttles descend in the hopper or magazine. When the bottom shuttle drops on to the trans- 10 ferrer (not now shown) occupying its forward position beneath the hopper or magazine, the starting weft-end of such shuttles passes below the bottom of the guide *a*, and when the said shuttle subsequently is trans- 15 ferrerred to the lay the transfer of the shuttle rearward takes the said starting weft-end rearward entirely clear of the guide, as well as of the horizontal portion *e* of the wire.

The space intervening between the guide 20 *a* and the adjacent edge of the rear wall of the outer portion or end of the hopper or magazine is sufficiently great to permit free introduction of the weft-end into the same at the top, and free movement of the weft- 25 end downward along the guide *a* as the shuttle descends within the hopper or magazine. Such space may be narrow, or in some cases it may be fairly wide as indicated in Fig. 3 of the drawings. In the latter cases 30 I have found it advisable to employ at the lower end of the said space means for preventing the shuttle which is next to drop upon the transerrer from rolling or tipping over as it makes its final drop. In the present 35 instance such means comprises a guide *h* having its acting portion set up close to the shoulder of the said shuttle, so as to prevent the rolling or tipping from taking place, there being sufficient distance between 40 the said acting portion of the said guide *h* and the adjacent portion of the weft-end guide *a* to permit the weft-ends to pass downward freely between the two guides. This guide *h* for the shuttle-ends is mounted 45 adjustably in position to enable its working position to be varied as may happen to be required in practice. To this end, it is furnished with an elongated stem passing through a hole at the lower end of a sup- 50 porting arm *i* that is mounted by means of a collar *k* upon the supporting rod 11 for the hopper or magazine. The arm *i* is fixed in the required position upon the supporting rod 11 by means of clamping screws *m*, *m*, 55 providing for securing it in the desired angular position upon the rod, that is to say toward or from the bottom shuttle occupying the hopper or magazine, and also in the required position longitudinally of the 60 rod. The stem of the guide *h* is adjustably held in place in the hole or socket which it occupies by means of a clamping screw *n*, this screw providing for adjustment of the 65 shuttles. The stem may be rotatably ad-

justed in the said hole or socket to set the acting portion of said guide forward or rearward as required.

The two ends of the hopper or magazine are mounted upon the supporting rod 11 by 70 means of ears *9^a*, *9^b*, projecting from them and having transverse holes therethrough enabling them to be fitted upon the rod, and the hopper or magazine is held in adjustable position lengthwise of the said rod by 75 means of collars *k*, *9^b*, held fixed in position upon the rod by clamping screws *m*, *m'*. As the reserve shuttles descend in the hopper or magazine and the starting weft-ends slide down the guide *a*, the portions of 80 such weft-ends that extend from the said guide to the weft-end holder 10 pass down between the rod 11 and the hopper or magazine, in front of such rod. As a shuttle is transferred from the hopper or magazine 85 to the lay, its starting weft-end becomes extended rearward beneath the rod 11 and thereby bent partly around such rod. When the just-transferred shuttle is first picked across the loom the inward movement there- 90 of draws its starting weft-end inward along rod 11 until it brings up against the ear *9^a* at the inner end of the hopper or magazine. In the inward movement of the said starting weft-end along the rod 11 it is deflected out 95 of engagement with the collar *9^b* by means of a guide *p* that extends outward from the adjacent hopper-support 14, with its free extremity inclined upward and rearward to such height with reference to the hopper- 100 supporting rod 11 that the starting weft-end in sliding inward beneath and in contact with said rod will pass under the said guide *p*, and be pressed down by the latter below and forward of the collar *9^b*, and con- 105sequently clear of the latter. The starting weft-end will then extend downward from the starting weft-end holder 10 to and partly around guide *p*, and from the latter obliquely downward, rearward, and inward 110 to the adjacent selvage of the web being woven. As usual, a weft-parter is employed for the purpose of severing or parting the said starting weft-end close to the selvage after the first pick of weft laid by 115 the fresh shuttle has been woven in. An ordinary temple weft-parter 12 is shown as employed for such purpose.

To keep the portion of the starting weft-end which remains connected with weft-end 120 holder, and which hangs down from the latter, out of the way of a shuttle which is being transferred to the lay, I provide a catcher for such portion or remnant. My present form of such catcher is shown at *o*, 125 in the shape of a wire that projects rearward from the hopper-support 14 at the inner end of the hopper or magazine. Its intermediate portion is depressed relative to its slightly elevated rear extremity. This catcher for 130

the hanging weft-end remnants occupies such a position that the movement of the just-transferred shuttle in first being picked which draws the weft-end of such shuttle 5 inward under the guide p also carries such starting weft-end into an inclined position over the catcher o . Consequently, when the starting weft-end is parted by the weft-parter 12 the loose portion of such weft-end 10 falls upon the catcher o . See Fig. 3. The guide p serves to hold the successive loose starting weft-ends forward upon the catcher o , in the downward bend thereof, as indicated in the case of the bunch of such weft- 15 ends that is shown in Fig. 3. The catcher o is located inwardly beyond the inner ends of the shuttles in the hopper or magazine, that is to say, between the said inner ends and the adjacent selvage of the web 20 being woven. In this position of said catcher the starting-end remnants hanging down from starting weft-end holder 10 and falling over catcher o are held by the said catcher out of the way of the reserve shuttles as 25 they successively are transferred from the bottom of the hopper or magazine to the lay. Thereby the said hanging remnants are prevented from fouling with said shuttles in the transfer. Guide p insures the move- 30 ment of the starting weft-end into position over and above the catcher o , so that following the parting of such weft-end adjacent the web-selvage the hanging remnant naturally will fall upon catcher o . 35 The second feature of invention referred to at the outset hereof is designed for employment in looms, such for instance as feeler-looms, in which ejection of the working weft-carrier takes place prior to complete exhaustion of the weft-supply carried 40 thereby. As already specified, this feature of the invention consists in improved means for insuring that the trailing weft-end, i. e., the portion of weft or filling extending from 45 the selvage of the web that is being woven to the ejected weft-carrier, shall be parted between such weft-carrier and the said selvage by the weft parting device that is employed for the purpose. The said means is ar- 50 ranged and operated, in the instances thereof that are shown herein, to place the said portion of weft or filling in position to be acted upon by the temple weft-parter 12. In case another kind of weft-parter should 55 be employed in practice, or one located in a position different from that occupied by said temple weft-parter 12, the said means will be arranged to place the said portion of weft or filling in position to be acted upon by the 60 particular weft-parter that is employed, in the particular location which such weft-parter occupies in the loom. The improved means in question includes a rod or wire ex- 65 tending from the breast-beam rearward, near the web-selvage at the side of the loom at 70

which ejection of weft-carriers takes place. This rod or wire is variously designated r , r^1 , r^2 , in the respective views in which the different embodiments are shown in the drawings. In accordance with my invention 75 I connect the said trailing-weft catcher rod or wire with an arm s of a rockshaft t which is mounted in bearings in connection with the front portion of the loom-frame. The trailing-weft catcher is controlled opera- 80 tively by the rockshaft, and is actuated through the rocking of the latter. In the position of the rockshaft and its arm that is shown in Figs. 1, 2, 5 and 7, the trailing-weft catcher is forward. Rocking of the rock- 85 shaft and its arm rearward into the position that is shown in Figs. 4, 6 and 8, moves the trailing weft-end catcher rearward, and in these latter views the said catcher is ready to engage the trailing weft-end of a weft- 90 carrier expelled from the lay. By forward rocking movement of the rockshaft and its arm from their position in Figs. 4, 6 and 8, the trailing-weft catcher is moved forward from its rearward position to present the 95 trailing weft-end to the weft-parter. The trailing-weft catcher is constructed suitably to insure the carrying of the trailing-weft end forward with it in being returned from the position of Figs. 4, 6 and 8 to that of 100 Figs. 1, 2, 5 and 7. This provision may be made in any of the ways heretofore proposed in the like connections. As convenient features of construction, the rear end of the short rod or wire r shown in Figs. 1 to 4 is 105 upturned for the said purpose, and each of the longer rods or wires r^1 , r^2 , of Figs. 5 to 8 is formed with an upbend at an intermediate point in its length. As will be apparent, rods or wires of different lengths are em- 110 ployed in the different embodiments of the invention. The rod or wire r of Figs. 1 to 4 is short, and while such rod or wire occupies its forward position, its rear end preferably is clear of the lay-beam in the advanced posi- 115 tion of the latter, but when the rockshaft and arm are rocked rearwardly the rod or wire is moved rearward so as to carry its rear end into proximity to the lay-beam in the rear position of the lay, as in Fig. 4. If 120 the lay should occupy a forward or partly forward position at the same time that the rod or wire r of Figs. 1 to 4 is rearward, the rear end of the rod or wire will occupy the transverse groove or slot 3^a, Fig. 2, in the top 125 of the lay-beam. The rods or wires of each of the other examples are sufficiently long to permit their rear portions to occupy the said groove or slot 3^a in all positions of the lay.

The trailing-weft catcher is arranged to 130 be lowered somewhat as it moves rearwardly, and to be raised as it moves forwardly. The lowering movement thereof is designed to insure that when rearward it shall be in a lowered position to enable it to engage from 135

below with the trailing-end of weft of the expelled weft-carrier, and the raising of the said catcher is designed to insure that the forward movement of the said catcher shall 5 present the trailing-end properly to the weft-parter. In the construction shown in Figs. 1 to 4 I show provisions for lowering and raising the trailing-weft catcher comprising a rotatable cam and connections between the same and the said catcher. In the constructions shown in Figs. 5 to 8 said cam and connections are not employed, the lowering and raising being effected by means of the movement of the rockshaft. 10 Referring first to Figs. 1 to 4,—in this construction the rod or wire r is pivoted by its front end at r^4 to the arm s of rockshaft t . The middle portion of its length fits between vertical guide-lugs of a guide-stand 20 fixed 15 upon the breast-beam, the rod or wire being adapted to play vertically between such guide-lugs, as well as to move longitudinally forward and rearward between them. The rear portion of the rod or wire r extends 20 over the top of a vertical rod 21, the upper portion of which passes through a guide-hole in the said guide-stand, the rod 21 being thereby held in vertical position and guided. 25 The lower end of the vertical rod 21 is connected with a lever 22 engaging with a rotatable cam 23. While the high parts of the said cam act against the lever 22, the rod 21 is held elevated and thereby gives the trailing-weft catcher-rod or wire r its raised position shown in Fig. 1. When the low part 30 of the cam 23 is presented to the lever 22, the rod or wire r occupies its lowered position as in Fig. 4.

In the construction shown in Figs. 5 and 40 6 the vertical movement of the trailing-weft catcher r' is due to the employment of a finger or secondary arm s' that is carried by the arm s of the rockshaft t . This finger or secondary arm projects rearward from the 45 arm s and under the catcher r' . In the rearward position of the arm and the catcher, shown in Fig. 6, the finger or secondary arm is lowered relative to the catcher, which occupies its lowered position, with its front 50 end supported by the pivot r^4 which connects such end to the arm s , and its rear portion resting upon the bottom of the transverse slot or groove a^3 in the lay-beam. When the rockshaft t is rocked so as to 55 swing the arm s forward from its position in Fig. 6 to that in Fig. 5 the finger or secondary arm s' is raised under the catcher r' and by making contact therewith raises its rear portion by swinging the catcher upward 60 around its pivotal connection r^4 with arm s , so that as the rockshaft arrives in its forward position the trailing weft-end catcher r' occupies the slightly-raised position shown in Fig. 5, and thereby presents properly to the weft-parter the trailing weft-end 65

that it has engaged and moved forward. The finger or secondary arm s' is mounted upon arm s with provision for adjustment to enable the extent of its lifting action to be varied. In the present instance such adjustment is effected by shift of the finger or secondary arm in its longitudinally adjusted position. 70

The construction shown in Figs. 7 and 8 differs from that of Figs. 5 and 6 in the employment of a guide r^3 upon the rear side of the lay-beam, through which guide the rear portion of the catcher r^2 extends, and in having the front end of said catcher in sliding engagement with pivot r^4 . The sliding 75 engagement is provided for by forming the said end of the catcher with a loop, the length of which extends upward and downward, the pivot r^4 entering the slot or opening of this loop. This slot or opening permits the front end of the catcher r^2 to play vertically with relation to the pivot r^4 . When the rockshaft and its arms occupy the 80 forwardly-rocked position in which they are shown in Fig. 7, the finger or secondary arm s' supports the catcher r^2 in a slightly raised position, with the lower end of its loop held up against the pivotal stud r^4 . When the rockshaft and arm are rocked rearwardly 85 into the position shown in Fig. 8, the movement of the finger or secondary arm s' downward away from the catcher r^2 permits the latter to lower until the upper end of its loop rests upon the pivotal stud r^4 , thereby 90 giving the catcher the required lowered rear position. When the rockshaft and its arm are rocked forward from its rearward position in Fig. 8, the contact of finger or secondary arm s' with the underside of the catcher r^2 operates to swing the said catcher 95 upward at its forward end, thereby producing the required bodily lifting movement of the catcher as it goes forward in the loom. 100

The rocking of the rockshaft t is timed to occur in the proper time-relation to the 110 ejection of the spent, or more properly nearly spent, weft-carrier. This is provided for in practice by operatively combining it with the devices which indicate for the said ejection or which are concerned 115 in effecting the latter. Since the ejection usually is performed as an incident to automatic replenishment of the working weft-supply, the rockshaft t is in practice indicated into action contemporaneously with 120 the indicating into action of the automatic replenishing mechanism, to operate in proper time-relation in respect of the replenishing operations. In the loom of the patent aforesaid, the rockshaft t is the rockshaft which is operated in shipping the driving power of the weaving instrumentalities into action and out of action, and is actuated automatically to rock the same in 125 one direction to unship the driving con- 130

nections of the weaving instrumentalities to suspend the ordinary weaving operations during the performance of the replenishing operations, and when the latter operations have been substantially completed it is similarly actuated to rock the same in the opposite direction to cause the weaving instrumentalities to resume the weaving operations. Accordingly, I have shown the trailing-weft catcher operatively combined with the rockshaft which in the loom of the patent aforesaid pertains to the shipper-means by which the weaving instrumentalities are shipped into inaction for the replenishment and into action following replenishment.

The proper timing of cam 23 is secured in this instance by reason of the said cam being carried by the change-shaft 3, and by reason of the position of the same upon the change-shaft. The change-shaft stands at rest during the ordinary weaving operations, and the cam 23 is so disposed thereon that while the change-shaft is thus standing at rest a high part of the cam immediately preceding a drop is in engagement with lever 22. This holds the trailing-weft catcher in its raised position during the ordinary weaving, and at such time the position of the rockshaft *t* keeps the said catcher forward. When the rockshaft is rocked to unship the weaving instrumentalities into inaction and move the trailing-weft catcher rearward, the contemporaneous starting of the change-shaft into rotation causes the high part of the cam 23 to pass away from lever 22 and the drop of such cam permits the catcher to become lowered, the result being the positions occupied by the parts in Fig. 4.

In the loom of the patent, when the weaving instrumentalities are shipped into action the rockshaft *t* and its arm *s* are rocked forward into the position in which they are represented in Figs. 1, 2, 5 and 7. They remain in such position during the regular weaving operation. Consequently, during the regular progress of the weaving the trailing-weft catcher is held in its forward and raised position shown in the said figures. When the detecting devices of the loom call or indicate the replenishing mechanism into action they also bring about the rocking of the rockshaft *t* and its arm *s* rearward from the said position to that shown in Figs. 4, 6 and 8. This rocking of the rockshaft brings about the shipping of the weaving instrumentalities of the loom into inaction, at the same time that the replenishing mechanism is called into action. The lay is caused to come to rest at or near back center, about where it is shown in the drawings. By the rocking of arm *s* with the rockshaft the trailing-weft catcher is moved rearward, and by the combined rear-

ward and lowering movement it is positioned as in Figs. 4, 6 and 8, namely with the upturned rear end of the first-described form of catcher close to and down in front of the lay-beam as in Fig. 4, and with the shoulder of either of the other forms in a closely corresponding position as in Figs. 6 and 8. When now, the front-plate 5 of the adjacent shuttle-box having been raised as in Figs. 4, 6 and 8, the nearly spent shuttle is pushed forward from the said shuttle-box and falls down in front of the latter, the portion of weft trailing from the said shuttle inward to and connected with the adjoining web-selvage is received upon the trailing-weft catcher, in front of its upturned end or shoulder. After a fresh or reserve shuttle has been transferred from the hopper or magazine to the open shuttle-box and the front-plate of the latter has been closed down, the forward rocking of the rockshaft *t* to ship the weaving instrumentalities into action again occasions the herein described forward movement of the trailing-weft catcher. The combined forward and rising movements of the said catcher cause it to carry the trailing weft-end forward and present the same to the weft parter, as before explained.

In the case of the trailing-weft catchers *r*¹, *r*², of Figs. 5 to 8, the portions thereof which extend over the lay-beam occupy the transverse groove *a*³ in the lay-beam, below the shuttle-race, so that the working shuttle in its movement slides upon the shuttle-race 100 above such portions of said catchers.

What is claimed as the invention is,—

1. The combination with a hopper or magazine, and a weft-end holder to which the starting ends of the reserve wefts extend rearwardly through between the weft-carriers in the hopper or magazine, of a weft-end guide which keeps the said starting ends beyond the portions of the weft-carriers which contact with one another, and causes the starting ends to pass through between the reduced end-portions of the latter, thereby obviating chafing of the starting ends by the said contacting portions.

2. The combination with a hopper or magazine having a guide or way for the ends of weft-carriers occupying the hopper or magazine, and a weft-end holder to which the starting ends of the reserve wefts extend rearwardly through between the said weft-carriers, of a weft-end guide alongside said guide or way arranged to keep the starting ends beyond the portions of the weft-carriers which contact with one another and to cause them to pass through between the weft-carriers beyond the said contacting portions, thereby obviating chafing of the starting ends by the contacting portions.

3. The combination with a hopper or

magazine, and a weft-end holder to which the starting ends of the reserve wefts extend rearwardly through between the weft-carriers in the hopper or magazine, of a weft-end guide located at the rear of said weft-carriers arranged to keep the said starting ends beyond the portions of the weft-carriers which contact with one another, thereby obviating chafing of the starting ends by 10 the said contacting portions.

4. The combination with a hopper or magazine, and a weft-end holder to which the starting ends of the reserve wefts extend rearwardly through between the weft-carriers in the hopper or magazine, of a weft-end guide arranged to keep the said starting ends from between the portions of the weft-carriers which contact with one another, constructed at top to permit the unobstructed looping of the starting ends around 20 the same and at bottom to permit escape of the said ends as the weft-carriers are called into service.

5. The combination with a hopper or magazine, and a weft-end holder to which the starting ends of the reserve wefts extend rearwardly through between the weft-carriers in the hopper or magazine, of a weft-end guide arranged to keep the said starting ends from between the portions of the weft-carriers which contact with one another, supported from the side and constructed at top to permit the starting ends to be looped around the same to engage 30 them with the guide, and at bottom to permit escape of the said ends as the weft-carrier are called into service.

6. The combination with a hopper or magazine, and a weft-end holder to which the starting ends of the reserve wefts extend rearwardly through between the weft-carriers in the hopper or magazine, of a weft-end guide arranged to keep the said starting ends from between the portions of the weft-carriers which contact with one another, and having at its top a beak to facilitate engaging a starting end therewith.

7. The combination with a reserve-shuttle hopper or magazine having a way or shuttle-guide of reduced width adjacent the delivery-eyes of the reserve shuttles, of a supplemental shuttle-guide at the lower end of said way or shuttle-guide arranged to engage with the side of a shuttle to prevent the latter from turning over in its descent.

8. The combination with a reserve-shuttle hopper or magazine having a way or shuttle-guide of reduced width adjacent the delivery eyes of the reserve shuttles, a weft-end holder to which the starting-ends of the reserve wefts extend rearwardly through between the reserve shuttles in the hopper or magazine, a weft-end guide arranged alongside said reduced way or shuttle-guide to 60 keep the said starting ends from between the

portions of the shuttles which contact with one another, and a supplemental shuttle-guide at the lower end of said way or shuttle-guide arranged to engage with the side of a shuttle to prevent the latter from turning 70 over in its descent.

9. The combination with a hopper or magazine, and a holder for starting-ends of weft, of a weft-end catcher, into immediate engaging relations with which the starting 75 end of a just-transferred weft-carrier is drawn by the first pick following the transfer, said weft-end catcher adapted to keep the hanging portion of the parted starting-end out of the path of weft-carriers subsequently transferred to the lay.

10. The combination with a hopper or magazine, and a holder for starting-ends of weft, of a stationary weft-end catcher located adjacent the web-selvage and into immediate engaging relations with which the starting end of a just-transferred weft-carrier is drawn by the first pick following the transfer, said weft-end catcher adapted to catch the hanging portion of the parted 90 starting-end and keep the same out of the way of weft-carriers subsequently transferred to the lay.

11. The combination with a hopper or magazine, and a holder for starting ends of weft located at the inner end thereof, of a weft-end catcher arranged to extend beneath and outside the weft-end stretched from the said holder to the adjacent web-selvage when the just-transferred weft-carrier is first picked, and to receive the hanging portion of such starting-end when parted at such selvage and keep such portion out of the way of the weft-carriers subsequently transferred to the lay.

12. The combination with a horizontal supporting rod, a hopper mounted on said rod, with a rod-engaging collar at the inner end of the hopper, and holding means for starting ends of weft, of a deflector by 110 which a starting end extending from said holding means partly around said rod is deflected clear of the rod-engaging collar as said starting end slides inwardly along the rod.

13. The combination with a horizontal supporting rod, a hopper mounted on said rod, with a rod-engaging collar at the inner end of the hopper, and holding means for starting ends of weft, of a weft-end catcher 120 arranged to extend outside a weft-end stretched from the said holding means to the adjacent web-selvage and to receive the hanging portion of such weft-end parted at such selvage and keep such portion out of the way of the weft-carriers in subsequent transfers to the lay, and a deflector by which a starting end extending from said holding means partly around said rod is deflected 125 clear of the rod-engaging collar as said 130

- starting end slides inwardly along the rod, said deflector also arranged to keep the hanging portion of the parted weft-end forward on the said weft-end catcher.
14. The combination with a hopper or magazine, and a holder for starting ends of weft, of a weft-end catcher which receives the hanging portion of a weft-end parted at the web selvage and keeps such portion from fouling with the weft-carriers in subsequent transfers to the lay, and a guide with which the weft-end becomes engaged as the first pick with a freshly transferred weft-carrier takes place, and by which the parted weft-end is held forward on the weft-end catcher.
15. The combination with a reserve-shuttle hopper or magazine having a way or shuttle-guide of narrow width adjacent the delivery-eyes of the reserve shuttles, a weft-end holder to which the starting-ends of the reserve wefts extend rearwardly through between the reserve shuttles in the hopper or magazine, and a weft-end guide arranged alongside said reduced way or shuttle-guide to keep the said starting ends from between the portions of the shuttles which contact with one another.
16. A weft-replenishing loom having shipper-means by which the weaving instrumentalities are shipped into inaction for the replenishment and into action following replenishment, and having a trailing-weft catcher operatively combined with the said shipper-means and operated by the latter to engage the weft trailing from an expelled weft-carrier and move such trailing weft forward toward the breast-beam.
17. A weft-replenishing loom having shipper-means by which the weaving instrumentalities are shipped into inaction for the replenishment and into action following replenishment, and a weft-parter, and also having a trailing-weft catcher operatively combined with the said shipper-means and operated by the latter to engage the weft trailing from an expelled weft-carrier and present such trailing weft to the weft-parter.
18. In a weft-replenishing loom having shipper-means by which the weaving instrumentalities are shipped into inaction for the replenishment and into action following replenishment, the combination with a rockshaft forming a part of the said shipper-means, of a trailing-weft catcher operatively controlled by the said rockshaft to cause the said catcher to engage the weft trailing from the expelled weft-carrier and move such trailing weft forward toward the breast-beam.
19. In a weft-replenishing loom having shipper-means by which the weaving instrumentalities are shipped into inaction for the replenishment and into action following replenishment, the combination with a rockshaft forming a part of the said shipper-means, and a weft-parter, of a trailing-weft catcher operatively controlled by the said rockshaft to cause the said catcher to engage the weft trailing from the expelled weft-carrier and move such trailing weft forward toward the breast-beam.
20. In a weft-replenishing loom having shipper-means by which the weaving instrumentalities are shipped into inaction for the replenishment and into action following replenishment, the combination with a weft-parter, and a rockshaft forming a part of the said shipper-means, of a trailing-weft catcher connected with said rockshaft moved toward weft-receiving position by rocking of the rockshaft in one direction and moved to present the trailing weft from an expelled weft-carrier to the weft-parter by rocking movement of the rockshaft in the other direction.
21. The combination with a rockshaft and an arm thereon, of a weft-catcher connected with said arm and moved rearward into position to receive a weft by rocking of said rockshaft in one direction and forward with the weft by rocking of the rockshaft in the reverse direction, and means to impart vertical movement to the weft-catcher.
22. The combination with a rockshaft and an arm thereon, and a weft-parter, of a weft-catcher connected with said arm and moved rearward into position to receive a weft by rocking of said rockshaft in one direction and forward with the weft to present the latter to the weft-parter by rocking of the rockshaft in the reverse direction, and means to impart vertical movement to the weft-catcher.
23. The combination with a rockshaft and an arm thereon, of a weft-catcher connected with said arm and moved rearward into position to receive a weft by rocking of said rockshaft in one direction and forward with the weft by rocking of the rockshaft in the reverse direction, and a second arm operating to produce vertical movement of the weft-catcher.
24. The combination with a rockshaft and an arm thereon, and a weft-parter, of a weft-catcher connected with said arm and moved rearward into position to receive a weft by rocking of said rockshaft in one direction and forward with the weft to present the latter to the weft-parter by rocking of the rockshaft in the reverse direction, and a second arm operating to produce vertical movement of the weft-catcher.
25. The combination with a hopper or magazine, and a holder for starting ends of weft located adjacent the inner end thereof, of a weft-end catcher located ad-

ja⁵cent the web-selvage in a position below and outside the normal line of draft of a starting end stretching from the weft-end holder to the said selvage, and adapted to keep the hanging parted starting end inward out of the path of transfer from hopper or magazine to lay.

In testimony whereof I affix my signature in presence of two witnesses.

SIMEON S. JACKSON.
